RAILWAY SWITCH

Filed Dec. 23, 1925

INVENTOR

ROBERT M. EVANS

BY

Richard J. Cook
ATTORNEY

UNITED STATES PATENT OFFICE.

ROBERT M. EVANS, OF SEATTLE, WASHINGTON.

RAILWAY SWITCH.

Application filed December 23, 1925. Serial No. 77,223.

This invention relates to improvements in railway switch construction and more particularly to a switch for rail roads laid in pavement; it being the principal object of the present invention to provide a double tongue switch from which the usual pivot pins for the switch tongues have been eliminated and wherein the tongues are provided with flanges throughout their lengths that are adapted to seat beneath the ball portions of the stock rails of the main or switch track in such manner as to effectively sustain the tongues and to distribute the pressure, that is exerted thereagainst, over an extended length as distinguished from sustaining the pressure at a single point, as is the case in constructions using the pivot pins for anchoring the switch tongues.

Other objects of the invention reside in the details of construction of the switch tongues and associated parts, the manner of and means for supporting the tongues functionally in position and the switch operating mechanism as described in the following specification.

In accomplishing these and other objects of the invention, I have provided the improved details of construction, the preferred forms of which are illustrated in the accompanying drawings, wherein—

Figure 1 is a plan view of a double tongue switch embodied by the present invention.

Figure 2 is an enlarged cross-sectional view taken substantially on the line 2—2 in Figure 1.

Figure 3 is a cross sectional view taken on line 3—3 in Figure 1.

Figure 4 is a perspective view of one of the switch tongues.

Referring more in detail to the several views of the drawings—

1 and 1' designate the rails of the main line track at one side of the switch, 1^a and 1^b the rails of main line track at the other side of the switch, 2 and 2' the rails of the switch track, 3 a stock rail that is laid as a continuation of rail 1 and which connects the latter with rail 2 of the switch track 3', a stock rail laid as a continuation of rail 1' and which connects it with rail 1^b of the main track, 4 and 4' are the switch tongues which, at their base end, connect, respectively, with rails 1^a and 2' and at their points are adapted to be moved into such relation with rails 3 and 3' as to cause cars moved thereover to be di-

rected onto the switch track or to continue on the main track. Guard rails 5 and 5' are spaced within the switch tongues, as is customary, and these are joined to the rails 3 and 3' by bed plates 6 which underlie them at each side of the switch. The bed plates extend the length of the guard rails, as shown in Figure 1, and are joined securely to the base flanges of the guard rails and rails 3 and 3' by rivets 7. The switch tongues are held in place by bearing against the guard rails 5 and 5' and rails 3 and 3' and thus the bed plates serve to prevent spreading apart due to lateral thrust incidental to switching from one track to the other.

The gist of the present invention resides principally in the details of construction of the switch tongues and in the means of support which makes possible the elimination of pivot pins at their base ends. They are supported for lateral, slideable movement upon filler blocks 8 that are disposed in close relation between the rails 3 and 3' and the guard rails adjacent thereto. These blocks are fitted snugly between the base flanges and vertical webs of these rails and rest upon the flanges and bed plates 6, as shown best in Figure 3, and thus serve as substantial supports for the tongues when in either switching position.

Along their outer edges the tongues are equipped with longitudinally extending flanges 10 which are adapted, when the tongues are in the different switching positions, to engage against the vertical webs beneath the ball portions of the rails 3 and 3', that is, when the tongues are in that position, as shown in Figure 1, which provides for cars passing through the switch in the direction of the arrow, to continue on the main track, the flange 10 formed along the outer side of tongue 4 bears, throughout the length of the tongue against the under side of the ball of rail 3, while if the tongues were moved to their other position to direct cars onto the switch track, the flange 10 on the outer side of tongue 4' would likewise bear against the under side of the ball of rail 3'. Thus, through the provision of these flanges, the tongues are held properly in place and the lateral pressure exerted against the tongues incidental to a switching operation is distributed over an extended length of the rails 3 or 3' and is not directed toward or sustained at any certain point. The flanges 10

are of sufficient width at the extreme base ends of the tongues that they are continually engaged with the rails 3 or 3' and thus retain these ends of the tongues properly alined with rails 1' and 2'.

Horizontally extending bolts 12 have their inner ends fixed in bosses 13, depending from the under sides of the tongues near their base ends, and extend outwardly through openings 14 in the webs of the rails 3—3' and at their outer ends have coiled springs 15 located thereabout to bear against the rails and nuts 16 at their outer ends of the bolts to yieldably retain the base ends of the tongues against inward movement. The bolts and springs are enclosed in casings 18.

Along their inner edges, toward the points of the tongues, they are likewise provided with laterally projecting flanges 19 adapted to bear beneath the ball portions of the guard rails 5—5' when in different switching positions. This construction provides that when a car is moving from the switch track onto the main track in a direction opposite to the arrow, the tongues are moved from position, as shown in Figure 1, to a position at which flange 19 of tongue 4 bears against the web and beneath the ball portion of guard rail 5. If cars are passing through the switch along the main track in a direction opposite to the arrow, the flange 19 of tongue 4' likewise bears against guard rail 5'. Thus, these latter flanges 19 serve to properly position the ends of the tongues with respect to the rails 3 and 3' for movement of cars in opposite directions and also sustain the tongues against movement too far inwardly.

At their movable ends the switch tongues are joined by a connecting rod 20 that holds them in proper spaced apart relation and by means of which they may be simultaneously actuated from one switching position to another. The rod 20 extends sufficiently to one side of the track for connection with a suitable actuating lever 21 or other switch mechanism whereby the tongues may be moved and held in set position. This lever or mechanism would be contained within a housing 22 and rod 20 would be contained in a housing 23.

Assuming that the switch is so constructed and that it is set as shown in Figure 1 for directing cars along the main track, the cars moving into the switch in the direction of the arrow are carried by tongue 4 and are guided by the tongue 4 and guard rail 5 while the tongue 4' is relieved of any function. If the switch is moved to direct cars onto the turnout track, the tongue 4' takes the lateral thrust and carries the car wheels from rail 1' to rail 2'. The switch may be manipulated for the operation of cars in either direction.

Having thus described my invention, what

I claim as new therein and desire to secure by Letters Patent, is:

1. In a railway switch, in combination with rails of a main track and a switch track, a stock rail, a guard rail spaced within the stock rail, a switch tongue disposed between the stock rail and guard rail having a horizontally projecting flange along one side thereof adapted, at the base end of the tongue, to engage with the stock rail as a means of retaining it in proper spaced relation thereto and in alinement with the switch rail, and, when the tongue is in switching position, to engage throughout its length with the under edge of the ball of the stock rail.

2. In a railway switch, in combination with rails of a main track and a switch track, a stock rail, a guard rail spaced within the stock rail, a switch tongue disposed between the stock rail and guard rail having a horizontally projecting flange along one side thereof adapted, at the base end of the tongue, to engage with the stock rail as a means of retaining it in proper spaced relation thereto and in alinement with the switch rail, and, when the tongue is in switching position, to engage throughout its length with the under edge of the ball of the stock rail, and a yieldable connection between the stock rail and switch tongue near its base end for preventing lateral displacement of that end of the tongue toward the guard rail.

3. In a railway switch, in combination with rails of a main track and a switch track, a stock rail, a guard rail spaced within the stock rail, a switch tongue disposed between the stock rail and guard rail having a horizontally projecting flange along one side thereof which at the base end of the tongue is adapted to engage with the web of the stock rail to retain it functionally in position, and when the tongue is in switching position, to engage throughout its length beneath the ball of the stock rail, said tongue being also provided along its opposite edge and near the point with a horizontally projecting flange adapted, when the tongue is not in switching position, to engage beneath the ball of the guard rail, and a yieldable connection between the stock rail and switch tongue near its base end.

4. In a railway switch in combination with rails of a main track and a switch track, a stock rail, a guard rail spaced within the stock rail, bed plates joining the bases of the stock rail and guard rail, blocks fitted between said stock and guard rails and a switch tongue movably mounted on said blocks for directing movement of cars along the main or switch track, said tongue having a horizontally projecting flange along one side thereof that is adapted at the base end of the tongue, to engage with the web of the stock rail to retain that end of the tongue.

properly in alignment with the rail with which it connects and when the tongue is in switching position to engage throughout its length beneath the ball of the stock rail; said tongue being provided also along its opposite edge and near the point with a horizontally projecting flange adapted to engage beneath the ball of the guard rail when not in switching position and a yieldable connection between the stock rail and switch tongue near its base end.

5. In a railway switch, a pair of stock rails leading from the rails of a main track at one side of the switch, respectively, to the outer rail of a switch track and to the outer rail of the main line track at the other side of the switch, a pair of guard rails spaced within the stock rails, switch tongues disposed between the stock rails and guard rails 10 and joining at their base ends with a rail

of the main line track and with a rail of the switch track; said tongues having horizontally extending flanges along their outer edges adapted, at the base ends of the tongues, to engage with the stock rails to retain them properly aligned with the rails to which they lead and adapted, when in one position, to engage beneath the ball portions of the stock rails, and having horizontally projecting flanges along their inner edges adjacent the points adapted, when in the other switching position, to engage beneath the ball portions of the guard rails, yieldable means connecting the switch tongues and stock rails near the base ends of the tongues 25 and means joining the movable ends of the switch tongues.

Signed at Seattle, King County, Washington, this 22nd day of October 1925.

ROBERT M. EVANS.
